DESIGN.

J. P. HARRIMAN.

Q.M. 18.362

ORNAMENTATION OF KNIT FABRICS.

UNITED STATES PATENT OFFICE.

JEREMIAH P. HARRIMAN, OF WOONSOCKET, RHODE ISLAND.

DESIGN FOR THE ORNAMENTATION OF KNIT FABRICS.

SPECIFICATION forming part of Design No. 18,362, dated June 5, 1888.

Application filed March 10, 1888. Serial No. 266,882. Term of patent 14 years.

To all whom it may concern:

Be it known that I, JEREMIAH P. HARRIMAN, a citizen of the United States, and a resident of Woonsocket, county of Providence, and 5 State of Rhode Island, have invented and produced a new and original Design for Surface Ornamentation of Knitted Fabrics, of which the following is a full, clear, and exact description, reference being had to the accompanying 10 photographic illustration, forming a part hereof, in which is represented a portion of a fabric with my design applied thereto.

My design is intended for application generally to all forms of knitted fabrics to which 15 it is desired to impart an ornamental appearance; and it consists in a series of parallelly-disposed denticulated stripes arranged diagonally of the fabric with respect to the rows of courses of loops composing the same, with a 20 series of small plain stripes interposed between the adjacent pairs of the former, all as will hereinafter more fully appear.

In the photographic illustration the denticulated stripes are shown at A A, &c., and the 25 smaller plain stripes at B B, &c. The denticulated stripes are indented on both edges, as shown, and are arranged in parallel relation

diagonally of the fabric with respect to the successive rows or courses of loops composing the same. These stripes, instead of being employed singly, are grouped in pairs, with the distance between the adjacent pairs thereof sufficiently great to receive a number of smaller plain stripes, B B, &c., which are interposed between them, the same being arranged in parallel relation with respect to the stripes A A, &c., and substantially covering the space between the adjacent pairs of the same. 30 35

Having thus described my invention, what I claim as new, and desire to secure by Letters Patent of the United States, is—

The design for surface ornamentation of knitted fabrics, consisting of a series of denticulated stripes arranged in pairs and disposed diagonally of the fabric, with a series of smaller 45 plain stripes arranged between the pairs of the former stripes, as shown and described.

In testimony whereof I have hereunto set my hand this 27th day of February, 1888.

JEREMIAH P. HARRIMAN.
